Attorney.

UNITED STATES PATENT OFFICE.

JOHN D. WARD, OF BRIGHTON, NEW YORK.

DESIGN FOR A THERMOMETER-CASE.

SPECIFICATION forming part of Design No. 24,860, dated November 5, 1895.

Application filed April 5, 1895. Serial No. 544,653. Term of patent 3½ years.

To all whom it may concern:

Be it known that I, JOHN D. WARD, of Brighton, in the county of Monroe and State of New York, have invented or produced a new and original Design for Thermometer-Cases, of which the following is a specification.

In the drawings, Figure 1 is a face view of the case. Figs. 2 and 3 are edge views. Fig. 4 is a cross-section in line $x x$ of Fig. 1.

The leading feature of my design is a double-ogee or scalloped form of the case in cross-section and a scroll at one or both ends.

A indicates the case. It is made of double-ogee or scalloped form in cross-section, as

shown at $b c d$, Fig. 4. At one or both ends 15 is a scroll a , formed by rolling the end over in circular form. The case made in this manner is of ornamental and pleasing form.

Having described my invention, I claim—
The design for a thermometer case herein 20 shown and described.

In witness whereof I have hereunto signed my name in the presence of two subscribing witnesses.

JOHN D. WARD.

Witnesses:

R. F. OSGOOD,
C. N. SMITH.
